UNITED STATES PATENT OFFICE

FRANCIS A. JACOBS, OF WARREN, OHIO, ASSIGNOR, BY MESNE ASSIGNMENTS, TO CHICAGO-CLEVELAND CAR ROOFING COMPANY, OF CHICAGO, ILLINOIS, A CORPORATION OF DELAWARE

CAR-UNCOUPLING DEVICE

Application filed May 31, 1923. Serial No. 642,392.

This invention relates to improvements in hand operated uncoupling devices for railway cars and the like, and more particularly to improvements in the parts that cooperate to lift the locking pin of the car coupler to uncouple the cars.

Objects of the invention are: to provide an uncoupling device, including brackets therefor, that is readily and easily assembled without requiring bending of any parts and which when assembled will remain in operative position until intentionally removed, and which is readily and easily removed without bending or straining any of the cooperating parts; the provision of a bracket formed of a single piece of metal into which the operating rod may be rotatably secured by merely setting the rod in slots in the brackets and inserting a key through said brackets so that one side of the key rests against the rod and the opposite side of the key may engage the bracket; the provision of a lifting rod having one end formed into a hub so that any movement of the coupler will not strain the connection between the lifting rod and the operating rod; the provision of an uncoupling device that is easily manufactured and assembled and at less expense than has heretofore been possible; and such other objects and advantages of the invention as may be found to obtain in the structures hereinafter described and claimed.

In the accompanying drawings, forming a part of this specification, and showing for purposes of exemplification, a preferred form and manner in which the invention may be embodied and practiced, but without limiting the claimed invention specifically to such illustrative instance or instances:

Figure 1 is a top plan view of an uncoupling device, embodying the invention, and showing the manner in which the device is applied to the end of the car;

Fig. 2 is an end elevational view of an uncoupling device embodying this invention;

Fig. 3 is a side elevational view showing in dotted lines the position of the uncoupling device in raised position;

Fig. 4 is a perspective view showing the

operating rod and lifting rod in assembled relation;

Fig. 5 is a top plan view showing the connection between the operating and the lifting rods;

Fig. 6 is an end view showing the manner in which the operating rod engages the lifting rod when in lifting engagement;

Fig. 7 is a perspective view of the bracket that rotatably secures the operating rod to the end of the car;

Fig. 8 is a top plan view of said bracket, showing a key therein;

Fig. 9 is a section taken on the line 9—9 of Fig. 8;

Fig. 10 is a perspective view of the key.

For purposes of illustration, I have shown on the drawings a wooden car end 11 to which brackets 12 are secured. These brackets, in the present instance, are made from a single piece of pressed steel and are formed to provide rear flanges 13 adapted to be secured to the car by fastenings 14. Extending out from the inner extremities of these flanges 13 is a member 15 that receives the operating rod. This member consists of side walls 16 joined together by a bottom wall 17, and the walls 16 are flanged inwardly at 18 to provide a top wall. The top flanges 18 and side walls 16 are cut away at 19 to provide an opening 20 into which the operating rod 21 may rest, in order to rotatably bear on the rounded lower edges of the opening 20 in said side walls 16. After the rod 21 is placed in the opening 20, a key 22 is inserted into the chamber 23 defined by the flanges 18, side walls 16 and bottom wall 17. When the key is inserted into the chamber 23 the bottom 24 thereof rests on the operating rod 21 and the top 25 makes contact with the flanges 18. The key is perforated, as at 26, so that a cotter pin 27 may be inserted through the key to prevent it from falling out. The bracket is pressed out at 28 in order to strengthen the junction of the side walls 16 and the flanges 13.

From the foregoing it will be apparent that the operating rod may be effectively secured on the end of the car without requiring bending of the coacting elements in assembling,

and that the assembly of the uncoupling devices is greatly facilitated.

The operating rod 21 is provided at one end with a crank arm 29, which when lifted rotates the operating rod 21 that lifts the lifting rod to raise the locking pin of the car coupler to unlock the coupler. The rod 21 is bent outwardly at 31 parallel with the coupler and this member 31 is bent upwardly at its end to provide a pintle 32.

The lifting rod 33 is bent back at one end to form a hook 34 that is passed through an eye 35 in the locking pin 36 of an uncoupling device 37. This hook insures operative connection between the lifting rod 33 and locking pin. The lifting rod 33 is of reduced diameter at 38 in order to allow some play between the rod and locking pin since the coupler is subject to lateral swinging movement at times.

At its other end the lifting rod is twisted or formed to provide an eye 39, that functions as a hub, integral with the rod 33, and the material beyond and below the eye is bent back at 41 in the direction of the main body of the lifting rod and towards the coupler, and in the present instance this return bend forms a stop 42 located directly below the main body of the rod 33.

The lifting rod 33 may be assembled on the operating rod by placing the rod 33 over and parallel with the portion 31, and placing the eye 39 over the pintle 32 and the hook 34 over the bend 43 in the rod 21, then swing the lifting rod 33 outwardly, away from the car end and towards the coupler. The bend 41 limits the outward movement of the lifting rod, and inward movement of lifting rod is limited by the coupler. The stop 42 limits the downward movement of the pintle 32, and therefore the device is capable of accommodating itself to the various movements of the coupler without danger of the parts accidentally becoming disengaged or rendered inoperative and without causing strains on any of the coating parts.

When the crank 29 is lifted, the rod rotates in the brackets 12 and the member 31 raises, causing the pintle 32 to grip through the eye 39 and the material forming the bend 41, thereby lifting the lifting rod 33 which raises the locking pin 36.

The invention as hereinabove set forth is embodied in a particular form of construction but may be variously embodied within the scope of the claims hereinafter made.

I claim:

1. A lifting rod for uncoupling devices for car couplers having a portion at one end adapted to engage a locking pin, and at its other end having a portion providing an eye and a stop member, said eye being adapted to receive a portion of that part of the uncoupling device with which it is intended to be associated, said stop member extending in the direction of and spaced laterally from the

main body of the rod and being adapted to prevent accidental disconnection of the rod from the said portion of the uncoupling device when the latter is in operative association therewith.

2. A lifting rod for uncoupling devices for car couplers having a portion at one end adapted to engage a locking pin, and having at its other end curled to form an eye and a stop member, said eye being adapted to receive a portion of that part of the uncoupling device with which it is intended to be associated, said stop member extending toward the car coupler and being adapted to prevent accidental disconnection of the rod from the said portion of the uncoupling device when the latter is in operative association therewith.

3. A lifting rod for uncoupling devices for car couplers having a portion at one end adapted to engage a locking pin, and having at its other end an eye and a stop member, said eye being adapted to receive a portion of that part of the uncoupling device with which it is intended to be associated, said stop member being disposed in substantially the same vertical plane, as the main body of the lifting rod and being adapted to prevent accidental disconnection of the rod from the said portion of the uncoupling device when the latter is in operative association therewith.

4. A lifting rod for uncoupling devices comprising a one-piece rod having integral means for engagement with the locking pin of a car coupler and having integral means bent to provide an eye and a stop, said eye being adapted to receive a portion of that part of the uncoupling mechanism with which it is intended to be associated, said stop being disposed below said eye and being adapted to prevent accidental disconnection of the rod from the said portion of the uncoupling device when the latter is in operative association therewith.

5. An uncoupling device, comprising, in combination: an operating rod having a plurality of arms; a lifting rod having a portion adapted to engage the locking pin of a car coupler; integral means curled on one of said rods providing an eye and a stop member; a portion of the other of said rods engaging in said eye, said stop member being adapted to prevent accidental disconnection of the rods while in operative association.

6. An uncoupling device, comprising, in combination: an operating rod; a lifting rod detachably connected to said operating rod; integral means on one of said rods providing a pintle; integral means on the other of said rods bent to provide an eye and a stop, said pintle extending into said eye and prevented by said stop from accidental disconnection from said eye.

7. An uncoupling device for car couplers, comprising, in combination: an operating

- rod having a plurality of cranks; a pintle on one of said cranks; a lifting rod having a hook at one end for the locking pin of the coupler, said lifting rod having at its other end an eye and a stop integral with said lifting rod; said stop being disposed in substantially the same vertical plane as the lifting rod, said eye and said stop being arranged to normally occupy positions on opposite sides
- 5 of the crank having the pintle.
- 10 8. In an uncoupling device for operating the lock of a car coupler, the combination with a rotatable lever having a plurality of crank arms, one of said crank arms extending forwardly from the car upon which the device is mounted and being provided with a pintle forming a vertical angle with said crank arm, of an auxiliary member interposed between said rotatable lever and the lock of
- 15 20 the coupler and adapted to actuate said lock, said auxiliary member being angularly disposed with respect to said forwardly extending crank arm and having its end bent to provide a hub formed integrally therewith which
- 25 receives the said pintle and being also provided with a guard member formed integrally with said auxiliary member, the said hub and guard member being arranged to normally occupy positions on opposite sides of the forwardly extending crank arm.
- 30 9. An uncoupling device, comprising, in combination: an operating rod; a lifting rod detachably connected to said operating rod; integral means on one of said rods providing
- 35 40 a pintle; integral means on the other of said rods curled to form an eye for receiving said pintle, and integral means on one of said rods forming a stop, for preventing accidental disconnection of the rods.
- 45 10. An uncoupling device for car couplers involving an operating rod, and a lifting rod, one of said rods having a crank arm, and the other having an eye adapted to cooperate with the crank arm, one of said members being provided with a stop below the eye and disposed in a vertical plane substantially normal to the crank arm for limiting upward movement of the eye with respect to the crank arm.
- 50 11. An uncoupling device for car couplers involving an operating rod having a crank arm, and a lifting rod having at one end a portion adapted to operatively engage the crank arm, and also having a stop member adjacent to said portion to limit upward movement of the lifting rod with respect to the operating rod, the stop member extending in the direction of the main body of the lifting rod toward the car coupler.
- 60

FRANCIS A. JACOBS.
